UNITED STATES PATENT OFFICE.

GEORGE W. HEATH, OF EAST ORANGE, NEW JERSEY.

DESIGN FOR A RADIODIAL.

Application filed September 12, 1924. Serial No. 10,762. Term of patent 7 years.

To all whom it may concern:

Be it known that I, GEORGE W. HEATH, a citizen of the United States of America, residing at East Orange, Essex County, and State of New Jersey, have invented a new, original, and ornamental Design for a Radiodial, of which the following is a specification, reference being had to the accompanying drawing, forming part hereof, in which Fig. 1 illustrates a perspective view

of a radiodial showing my new design and Fig. 2 is a view of a portion of said dial showing detail of my design.

I claim:

The ornamental design for a radiodial as shown.

Signed at New York city, N. Y., this 8th day of September, 1924.

GEORGE W. HEATH.
